(57) **CLAIM**

The ornamental design for an accessory mounting system, as shown and described.

DESCRIPTION

FIG. 1 is a front view showing the accessory mounting system design.

FIG. 2 is a right side view showing the accessory mounting system design.

FIG. 3 is a left side view showing the accessory mounting system design.

FIG. 4 is a top view showing the accessory mounting system design.

FIG. 5 is a bottom view showing the accessory mounting system design.

FIG. 6 is a rear view showing the accessory mounting system design; and,

FIG. 7 is a perspective view showing the accessory mounting system design.

The broken line showing of an accessory mounting system is for the purpose of illustrating portions of the article and forms no part of the claimed design.
